United States Patent Office

Des. 185,648
Patented July 7, 1959

185,648

COVER HANDLE

Wayne F. Rudebeck, Manitowoc, Wis., assignor to Mirro
Aluminum Company, Manitowoc, Wis., a corporation
of New Jersey

Application May 19, 1958, Serial No. 50,949

Term of patent 3½ years

(Cl. D44—29)

Fig. 1

Fig. 2

Fig. 3

Fig. 4

Fig. 5

Figure 1 is a side elevational view of my design of a cover handle and showing illustratively in broken lines a cover to which it is attached;

Figure 2 is an enlarged top plan view of my design of a cover handle;

Figure 3 is a side elevational view of the handle;

Figure 4 is a bottom plan view of the handle; and

Figure 5 is a view of the left end of the handle as shown in Figure 3 looking in a direction toward the right.

I claim:

The ornamental design for a cover handle, as shown and described.
